EARTH BORING MACHINE
Bertrand N. Weber, Green Isle, Minn.
Filed Nov. 9, 1959, Ser. No. 851,681
2 Claims. (Cl. 175—106)

This invention relates to an apparatus for boring a hole in the earth in which a tile type conduit is placed.

An object of this invention is to provide a novel apparatus, of simple and inexpensive construction, for readily boring a hole in the earth in which a large tile type conduit is placed.

Another object of this invention is to provide a power driven apparatus for readily boring a hole in the earth in which a tile type conduit is placed and arranged and constructed to be mounted on the tile in a manner to leave substantially the entire inside of the tile free of the apparatus to thereby permit workmen to work within the interior of the tile.

A still further object of this invention is to provide a novel rotary boring apparatus arranged and constructed to be mounted adjacent the front end of a tile type conduit and serving to bore a hole in the earth substantially the same size as the tile to thereby permit the tile to be placed therein whereby grouting is obviated.

Another object of this invention is to provide an earth boring apparatus having a rotary cutting head for boring a hole in the earth in which a large tile type conduit is placed and including a conveyor mechanism cooperating with the cutting head for continuously conveying loosened earth outwardly of the tile.

A more specific object of this invention is to provide a power operated conveyor device including a plurality of reciprocating conveyor elements arranged and constructed to progressively and continuously convey material in a predetermined direction.

These and other objects and advantages of this invention will more fully appear from the following description, made in connection with the accompanying drawings, wherein like reference characters refer to the same or similar parts throughout the several views, and in which:

FIG. 1 is a longitudinal vertical section of a pair of tiles positioned in a hole in the earth with the novel earth working apparatus shown partly in side elevation and partly in section;

FIG. 2 is an enlarged end elevational view of the cutting head shown at the right side of FIG. 1;

FIG. 3 is a cross sectional view taken on line 3—3 of FIG. 2; and

FIG. 4 is a horizontal longitudinal section of a tile showing the top plan view of a portion of the conveyor device.

Referring now to the drawing and specifically to FIG. 1, one embodiment of the novel earth working apparatus, generally designated as 10, is shown mounted within the forwardmost of a pair of tiles T which have been positioned within a hole H. It is to be understood that the term "tile" is intended to include the large conduits or pipes formed of tile, metal or other material and which are commonly used as water conduits beneath roadbeds or the like.

The novel earth boring apparatus 10 includes a rotary cutting head in the form of a cog wheel 11 which as seen in FIG. 2 is comprised of a pair of semi-circular segments 12 detachably secured together and each having a peripheral flange 13 extending outwardly therefrom. Each of the segments 12 is also provided with a plurality of openings 14 arranged around the periphery thereby to define a plurality of cogs or teeth 15.

Cog wheel 11 is provided with a hub 16 which includes a sleeve 17 having an annular flange 18a extending radially

2

ally from the front end thereof and having an annular flange 18b extending radially from the rear end thereof. A plurality of spiders or spokes 19 are secured to front flange 18a of hub 16 and extend radially outwardly therefrom and are secured to a peripheral flange 13 of cog wheel 11. It will be seen that two of the spokes 19 have an arcuate member 20 secured transversely thereof as by welding. Arcuate members 20 are detachably secured to the flange 13 by bolts 21 and serve to hold the ends of the semi-circular segments 12 in abutting relation.

Spokes 19 extend radially outwardly beyond the outer edge of flange 13 and are provided with digging elements or teeth 22 at the outer ends thereof and which extend axially forwardly of the cog wheel 11 as best seen in FIGS. 2 and 3. Cog wheel 11 is also provided with a plurality of digging teeth 23 which, as seen in FIG. 2, are arranged at varying distances from the axis of the cog wheel.

Referring now to FIG. 2, it will be seen that when cog wheel 11 is rotated, teeth 22 define a circle having a diameter only slightly larger than the diameter of tile T. Thus teeth 22 and 23 cooperates to bore a hole only slightly larger than the size of tile T. Cog wheel 11 is also provided with a pair of paddle members 24 each being secured to the spoke 19 and arranged in radially opposed relation with respect to each other. It will be noted that each of paddle members 24 extend obliquely to the rear of the face of the cog wheel. Paddle members 24 function to direct earth rearwardly into the tile which, of course, facilitates the boring operation. It should also be noted that the unique detachable construction of the semi-circular segments 12 permit the cutting head or cog wheel 11 to be radially disassembled when the cutting head engages an obstruction such as a rock or the like. The obstruction may be removed and the cutting head may be quickly re-assembled for operation thereof.

Hub 17 is rotatably mounted upon an elongated tubular member or pipe 25 which as seen in FIG. 1 projects forwardly of the cog wheel 11 into penetrating relation with the earth. A pair of mounting members 26 each being of substantially channel-shaped cross sectional configuration includes a web portion 27 and a pair of flanges 28 formed integrally therewith. It will be seen that the outer ends of the web portion 27 of each of the mounting members 26 have an arcuate plate 30 secured thereto and each of which is provided with threaded apertures formed therein. These apertures in plates 30 receive bolts 31 which may be tightened into engaging relation with the inner circumferential surface of the tile T so that the elongate shaft 25 may be secured therein in substantially co-axial relation. It should be noted that elongate shaft or pipe 25 not only serves as a mounting for the cog wheel but also functions to guide the cutting head during the boring operation. In some instances, the elongate member 25 may be forced completely through the portion of the earth in which a tunnel is to be made so that the course or disposition of the hole to be bored may be predetermined.

It will be seen from FIGS. 2 and 3 that tile T is provided with an annular shoulder spaced inwardly from the leading edge thereof and against which the outer end portions of web 28 of the front mounting member 26 are disposed.

Power means are provided for rotating cog wheel 11 and include a pair of drive mechanisms 32, as best seen in FIGS. 2 and 3. Each of the drive mechanisms 32 include a hydraulic motor which is provided with a flexible inlet supply conduit 34 and a flexible outlet supply conduit 35 which are each connected to a source of hydraulic power, not shown. Hydraulic motor 33 is provided with a drive shaft 36 having a pair of universal joints 37 to permit the drive shaft 36 to be flexed. The

flexible characteristic of drive shaft 36 facilitates mounting of the drive mechanism 32 in driving relation with the cog wheel. A driven element or gear 38 is affixed to the outer free end of drive shaft 36 and engages cogs 15 of cog wheel 11.

Each of the drive mechanisms 32 are provided with mounting means for releasably clamping the drive mechanism against the upper inner circumferential surface of the tile T. Each of the mounting means includes an elongated mounting member or bar 39 having a bracket 40 secured thereto adjacent its rear end portion and which is secured to the housing of hydraulic motor 33. Mounting bar 39 has a pair of bearing sleeves 41 secured thereto and which serve to support intermediate portions of flexible drive shaft 36. A pair of hook elements 42 are affixed to opposite edges of mounting bar 39 at the front end thereof and are disposed in substantially opposed parallel relation, as seen in FIGS. 2 and 3. Each of the mounting means also includes an elongated channel-shaped supporting member 43 positioned upon the upper outer side of tile T. The front end of support member 43 has a bracket 44 secured thereto as by welding and which is disposed just forwardly of the leading edge of tile T. A plate 45 is secured to bracket 44 by bolts 47 or the like and has a pin 48 secured transversely thereof and extending laterally outwardly from the sides of the plate, as best seen in FIG. 2. Bracket 45 is provided with a pair of vertical slots through which bolt 47 extends so that plate 45 may be adjusted vertically.

Pin 48 is releasably engaged by hook elements 42 so that mounting bar 39 may be swung into abutting relation with the inner circumferential wall of tile T. A pair of bolts 49 each pass through registering apertures formed in the mounting bar 39, support member 43 and tile T and are secured in place by lock nuts 50.

When each of the drive mechanisms 32 are swung into abutting relation with the inner circumferential surface of tile T and secured thereto in the manner illustrated in FIG. 3, the gear 38 is positioned in engaging relation with the cogs 15 of cog wheel 11. By employing hydraulic motors as the power means, a relatively small unit may be used which has a relatively large horsepower output during normal operation. This is especially important when boring holes, for example, beneath road beds for placing tile type conduits therein. Ordinarily during the boring operation, workmen are required to be stationed within the tile at five foot intervals for shoveling the loosened earth outwardly through the rear end of the tile. It will therefore be seen that by employing the pair of hydraulic motor type drive mechanisms, a minimum amount of space is used and a better balanced driving effect on cog wheel 11 is obtained. Referring now to FIG. 1, it will be seen that the inlet and outlet conduits supplying the hydraulic motors are the only parts of the drive mechanism which are disposed within the rearmost of the tiles.

Referring now to FIG. 1, it will be seen that means are provided for urging the tiles T inwardly of the hole H during the boring operation. A hydraulic ram or jack 51 is positioned against a block B and includes a piston rod 52 having an enlarged head portion 53 affixed to its outer end. The head portion 53 bears against another block C which is disposed in abutting relation with the rear edge of the rearmost tile T. By extending piston rod 52 the tiles T are urged into the hole H in end-to-end relation as the hole is being formed by the novel boring apparatus. Although not shown in the drawing, the flexible inlet and outlet supply conduits 34 and 35 are provided with suitable coupling means to permit the conduits to be uncoupled when each successive tile is positioned for entry into the hole. This arrangement permits the drive mechanism to remain intact in the forwardmost of the tiles T when an additional tile is being positioned in place for entry into the hole which, of course, results in a great saving of time and labor.

A conveyor device, generally designated 54, is also provided for conveying earth rearwardly and outwardly of the tiles T during the boring operation. Conveyor device 54 includes a plurality of elongate conveyor channels 55 each having a bottom wall 56 and opposed side walls 57. Channels 55 have their ends disposed in overlapped relation and are detachably secured together by bolts 55a. Referring now to FIG. 2, it will be seen that bottom wall 56 is of arcuate configuration in cross sectional shape to conform to the curvature of the inner surfaces of tiles T. A stop element 58 is secured to the underside of bottom wall 56 adjacent one end thereof and is adapted to engage the leading edge of the tile for retaining conveyor channel 55 against rearward longitudinal movement as best seen in FIG. 3.

A frame structure 59 is positioned upon the upper free edges of side walls 57 and is arranged for reciprocating movement in a fore and aft direction relative thereto. Frame structure 59 is comprised of a plurality of frame members 60 pivotally connected together and each including a pair of laterally spaced longitudinally extending members 61 interconnected by a pair of transversely extending cross members 62. The forward ends of each of the longitudinally extending members 61 are bifurcated as at 63 and receive therebetween the rear ends of longitudinally extending members 61 of the next adjacent frame member. A vertical pivot pin 64 secures the ends of the respective longitudinal members together in a tongue and groove type connection to thereby permit pivoting about a substantially vertical axis.

Each of the transverse members 62 is provided with a pair of transversely spaced lugs 65 secured to the underside thereof. A conveyor element or blade 66 is secured to the lugs 65 of each transverse cross member 62 by means of pivot pins 67. It will be noted that the conveyor elements or blades 66 have arcuate shaped lower edges to conform to the arcuate shape of bottom wall 56. Referring now to FIG. 3, it will be seen that the upper portion of each of the conveyor elements 66 defines a stop 68 which cooperates with cross member 62 for limiting pivotal movement of the conveyor element 66 in a forward direction or swinging movement toward the right side of FIG. 3. Conveyor elements 66 may pivot about pin 67 in a fore and aft direction but are limited in their forward swinging movement to the inclined position illustrated in FIG. 3.

Power means are provided for causing reciprocating movement of frame structure 59 and comprises a double-acting hydraulic ram 69 having control means 69a and including a piston rod 70 pivotally connected adjacent its ends to frame structure 59 as at 71. Hydraulic ram 69 is removably mounted on the rearmost of channels 55 and is provided, of course, with an inlet supply conduit 72 and an outlet conduit 73 which are connected to a source of hydraulic power. It will be noted that the rearmost channel 55 is supported in inclined relation with respect to the rearmost tile by a pair of cables 74 which have one of their respective ends detachably secured to the channel as at 75 and have their other end secured to the tile by an eye bolt 76. Extension and retraction of piston rod 70 imparts reciprocating movement to frame structure 59 in a fore and aft direction. As frame structure 59 moves rearwardly or to the left, as is seen in FIG. 3, the conveyor elements 66 are maintained in their inclined position and will cause loosened earth disposed within the conveyor channel 55 to be moved continuously and progressively toward the rear of the tile T. When the piston rod 70 of hydraulic ram 69 is extended, the frame structure 59 is caused to move forwardly or to the right as seen in FIG. 3 and conveyor blades or elements 66 will pivot rearwardly or to the left about the transverse axis when they encounter material disposed within their path. It will therefore be seen that during the boring

operation, paddle members 24 will direct the loosened earth into the tile T and into the conveyor channel 55 so that the material will thereafter be conveyed rearwardly and outwardly of the tiles by the conveyor elements 66. When it is desirable to position another tile 5 for entry into the hole, the hydraulic ram 69 is detached from the rearmost conveyor channel 55 and is also detached from frame structure 59. Cable means 74 are then detached from the tile and from the rearmost channel and the next tile is positioned in place for entry 10 into the hole. With this arrangement, it will be seen that it is not necessary to retract the entire conveying mechanism 54 from the tile when each successive tile is positioned for entry into the hole.

It will be seen from the foregoing description that my 15 novel earth boring apparatus is arranged and constructed to bore a hole substantially the same size of a large type conduit so that the tile may be placed within the hole without the necessity of grouting. It will also be noted from the preceding paragraphs that the drive mechanism 20 for driving the rotary cutting head is adapted to be uniquely mounted to the tile in a manner to require a minimum of space so that the interior of the tile is accessible to workmen for working therein.

One of the long existing problems associated with 25 earth boring apparatus of the type described herein has been the time lost when the boring apparatus encounters an obstacle. It will be seen, however, that my novel earth boring apparatus includes a segmented cutting head which may be readily disassembled when an obstacle 30 is encountered to thereby permit the removal of the obstacle. It will also be seen that I have provided a conveyor device cooperatively associated with the cutting head for progressively and continuously conveying material outwardly of the tile conduits during the boring operation. Thus it will be seen that I have provided a 35 novel earth boring apparatus which, because of its unique construction and operation, permits a great saving of time and labor.

It will, of course, be understood that various changes 40 may be made in the form, details, arrangement and proportions of the parts without departing from the scope of this invention which consists of the matter shown and described herein and set forth in the appended claims.

What is claimed is:

1. Apparatus applicable to the leading front end of a 45 pipe tile and for producing a hole in the earth into which the tile is to be moved,

said apparatus including a forwardly facing rotary cutter having a cutting diameter substantially equalling the diameter of the tile to be placed into the bored hole, mechanism mounting and driving the cutter adjacent

the front end of the tile and including an elongate rotary member drivably connected to the cutter and extending rearwardly therefrom within the outer periphery of the cutter and applying driving torque to said cutter to revolve the cutter against the earth at a location immediately adjacent the front end of the tile, said mechanism also including a motor having a frame and also having an output shaft connected with and driving said rotary member, said mechanism also including a tile engaging mount adapted to be applied in fixed position upon the tile, said mount having an earth and tile-engaging element spaced rearwardly from the cutter and disposed substantially at the outer periphery thereof, said element extending rearwardly to lie along and flush against the outer periphery of the tile in clamping relation therewith to thereby be restrained by the tile and by the earth at the periphery of the bored hole from moving around the rotation axis of the cutter, said mount having means retaining said element in fixed position on the outer periphery of the tile, said mechanism also including rigid means secured on said mount and rotatably mounting said rotary member and retaining said motor frame in fixed relation on said mount to prevent rotation of the motor frame with respect to the tile and earth as the cutter is revolved, whereby to produce a hole in the earth immediately in front of the tile to permit the tile to be moved thereinto.

2. The invention set forth in claim 1 wherein said earth and tile-engaging element of the amount also has earth-engaging surfaces facing transversely and circumferentially of the rotation axis and circumferentially of the tile, whereby to be obstructed from circumferential movement by the earth as the cutter engages the earth in a cutting action.
